UNITED STATES PATENT OFFICE

HERBERT S. STARK, OF HARRIS, MINNESOTA

COMBUSTION-ENGINE SPEED GOVERNOR

Application filed April 26, 1928. Serial No. 272,981.

This invention relates to new and useful improvements in speed governors for combustion engines and aims to provide a novel and simply constructed governor mechanism primarily, though not specifically adaptable for association with the Ford automobile engine so as to prevent the engine from racing, and to automatically maintain a uniform speed of the engine regardless of the load applied thereto. An important object of this invention is to improve and simplify governors of this general variety that have previously been patented and in some instances placed upon the market.

Furthermore, the nature of this invention is such as to permit of its attachment to the engine by unskilled persons, and that may be operatively associated with the usual engine fan pulley so as not to interfere with the operation of the engine properly, which is not the case in the use of some governors that are adapted to be operatively associated with the engine timing mechanism.

A further and important object is to provide means as a part of the governor whereby various speeds of the motor may be attained.

With the foregoing and other objects in view as the nature of the invention will be better understood, the same comprises the novel form, combination and arrangement of parts hereinafter more fully described, shown in the accompanying drawings and claimed.

In the accompanying drawings wherein like reference characters indicate corresponding parts throughout the same:

Figure 1 is a fragmentary plan view partially in cross section of a well known type of internal combustion engine equipped with my improved speed governor.

Figure 2 is a bottom side perspective of the member constructed for association with the butterfly valve arm so as to cause the opening and closing movement of the butterfly valve when a load is placed upon the engine or relieved therefrom.

Figure 3 is a perspective view of the connecting rocker shaft between the governor

unit per se and said valve arm associated member.

Figure 4 is a perspective view of the supporting frame for the governor unit per se.

Figure 5 is a fragmentary section through a portion of the frame disclosing one of the shaft bearings associated therewith.

Figure 6 is a transverse cross section through the governor unit per se.

Figure 7 is a transverse section through said unit disclosing the manner of association of the adjacent end of the rocker shaft with the sliding member of the governor unit, and

Figure 8 is a perspective of a supporting bracket that constitutes one of the features of the device.

Now having particular reference to the drawings, A designates fragmentarily a well known type of internal combustion engine, the intake manifold of which is equipped with the usual fuel regulating butterfly valve *a* controlled by the movement of a valve arm *b* at the outer side of the manifold.

The usual fan belt pulley at the forward end of the motor is designated by the reference character *c*. The present invention consists of a relatively U-shaped shaft supporting frame 5, the opposite end legs of which are bent rearwardly upon themselves to provide a pair of arms 6-6 that diverge upwardly with respect to the legs of the frame.

The innermost arm is provided with an opening whereby to permit it to be bolted to the side of the motor A at its front end and at the side opposite that equipped with the intake manifold, the horizontal bar portion of the frame 5 resting against the side of the motor, as clearly disclosed in Figure 1. The end of the outermost arm 6 is twisted over to provide a flat bracket having an opening therein to facilitate the attachment of this arm to the motor at the point of connection between the inlet of the water jacket and the outlet of the water pipe from the radiator, see Figure 1.

Arranged within the bight portion between the arms 6-6 and the legs of said frame 5 are shaft bearings 7-7, these bear-

ings being retained within the bight portions by metal straps 8 having rounded and threaded ends for engagement through openings within the frame legs as well as the arms 6—6 integrally associated therewith, nuts 9 being threaded upon said threaded ends as more clearly disclosed in Figure 5. Journaled within these bearings 7—7 is the shaft 10 of a governor unit 11, the forward end of the shaft extending beyond the forward bearing being equipped with a belt pulley 12.

Pivoted to the shaft 10 at its inner end is a pair of weights 13—13 that are operatively associated with a collar 14, slideable upon said shaft, which collar is associated with a circumferential groove to loosely receive an inverted U-shaped yoke 15. Pivoted to opposed points of this yoke is an upwardly extending fork 16 to the upper end of which is keyed one end of a rock shaft 17. This rock shaft is extended transversely across the top of the motor A, the same being guided by a suitable bracket 18 associated with the outermost arm 6 of the governor supporting frame 5, said shaft being further guided and supported by a bracket 19 arranged upon the top side of the motor, see Figure 1.

For association with the arm *b* of the butterfly valve *a* there is provided a triangular shaped plate 20, the wide end of which is provided with a pair of spaced ribs 21—21 between which the said arm *b* is arranged and secured therein by a cotter pin 22 or other suitable means. The outer narrow end of this plate 20 is provided with an opening, while loosely engaged therein is a forwardly extending connecting rod 23, the front end of this connecting rod being pivotally associated with the downwardly extended cranked end 24 of said rock shaft 17. Arranged upon the side of the motor adjacent the intake manifold and at the forward end thereof is an L-shaped bracket 25, through an opening in the outer end of which extends an elongated threaded pin 26, and upon the outer end of which is threaded a wing nut 27. The inner end of this pin is attached to a retractile coil spring 28, while the inner end of said spring is connected to the valve arm plate 20, by a connecting pin 29, this spring normally maintaining a pull upon the plate 20 so as to maintain the butterfly valve *a* in open position. Trained over the pulley 12 of the governor shaft 10 and the fan pulley C is a belt 30 for imparting rotation to the shaft 10 of said governor. Obviously during the operation of the engine the shaft 10 will be rotated, throwing the weights 13—13 outwardly for sliding the collar 14 inwardly upon said shaft 20.

This action will cause the rocking of the shaft 17 so as to push upon the connecting

rod 23 moving the butterfly valve *A* in a closing direction against the action of the spring 28, preventing the motor from racing, and maintaining a uniform speed regardless of the load thereon. Obviously as the load upon the motor increases, the speed thereof decreases, resulting in the opening of the valve a predetermined extent so as to bring up the speed of the motor to the proper degree, and vice versa.

The speed of the motor may be regulated at will by an adjustment of the thumb nut 27 which will increase or diminish the tension of the spring 28.

Having thus described the invention, what I claim as new and desire to secure by Letters Patent is:—

1. A support for governors including a rotary shaft; a U-shaped frame constructed of sheet metal, the leg portions of the frame being bent at their intermediacies in acute angular positions, an annular shaft bearing body for disposition within the crotch of each leg, an arcuate securing element for each bearing body, said element being threaded at each end and disposed through openings in the angularly disposed portions of the leg, and nuts on the ends of the securing elements to prevent displacement thereof.

2. A support for governors including a rotary shaft; a U-shaped frame, the leg portions of the frame being bent at their intermediacies in acute angular positions, an annular shaft bearing body for removable disposition within the crotch of each leg, one end of each bearing body being provided with a flange for abutment against the crotch portion of the corresponding leg and a securing element to prevent accidental displacement of the said body, the free ends of the U-shaped frame being adapted to be secured to a suitable supporting structure.

In testimony whereof I affix my signature.

HERBERT S. STARK.
